Primary Examiner — Kelley Donnelly(74) *Attorney, Agent, or Firm* — Volpe and Koenig, P.C.(57) **CLAIM**

The ornamental design for a fridge shelf display device, as shown and described.

DESCRIPTION

FIG. 1 is a front view of the invention;

FIG. 2 is a top view of the invention shown in FIG. 1;

FIG. 3 is a right side view of the invention shown in FIG. 1;

FIG. 4 is a left side view of the invention shown in FIG. 1; and,

FIG. 5 is a perspective view of the invention shown in FIG. 1.

1 Claim, 2 Drawing Sheets
